UNITED STATES PATENT OFFICE

EDWIN E. SLICK, OF PITTSBURGH, PENNSYLVANIA

DESIGN FOR A CAKE PLATE OR SIMILAR ARTICLE

Application filed September 4, 1929. Serial No. 32,667. Term of patent 14 years.

To all whom it may concern:

Be it known that I, EDWIN E. SLICK, a citizen of the United States, residing at Pittsburgh, in the county of Allegheny and State of Pennsylvania, have invented a new, original, and ornamental Design for Cake Plate or Similar Article, of which the following is a specification, reference being had to the accompanying drawings, forming a part thereof and in which:

I claim:

The ornamental design for a cake plate or similar article, substantially as shown.

In witness whereof, I have hereunto set my hand.

EDWIN E. SLICK.
